UNITED STATES PATENT OFFICE.

CHARLES A. HOYT, OF CLEVELAND, OHIO, ASSIGNOR TO THE NATIONAL COMPUTING SCALE COMPANY, OF SAME PLACE.

DESIGN FOR A SCALE-FRAME.

SPECIFICATION forming part of Design No. 28,310, dated February 22, 1898.

Application filed November 1, 1897. Serial No. 657,128. Term of patent 14 years.

To all whom it may concern:

Be it known that I, CHARLES A. HOYT, a citizen of the United States, residing at Cleveland, in the county of Cuyahoga and State of Ohio, have invented and produced a new and original Design for a Frame for Beam-Scales, of which the following is a specification, reference being had to the accompanying drawings, forming a part thereof.

10 Figure 1 is a perspective view of a scale-frame, showing the essential features of my new design; and Fig. 2 is a horizontal sectional view on line 2 2 of Fig. 1.

The scale-frame consists of a substantially 15 rectangular base A, two standards B B, which rise from the base, near the rear corners thereof, and a substantially rectangular skeleton frame C, supported by the standards.

The material and novel features of the design, however, reside in the form and relative

arrangement of the two standards. The lower parts b of these standards are bowed inward toward each other, and the upper parts b' thereof are substantially vertical, and in this form and relative arrangement of the standards are found the material features of the design which this patent is designed to cover.

The standards in horizontal section may be substantially U-shaped, as shown in Fig. 2, the convex side being outermost.

Having described my invention, I claim—
The design for a scale-frame as herein shown and described.

In testimony whereof I affix my signature in presence of two witnesses.

CHARLES A. HOYT.
